Letters Patent No. 556 Dated Apr. 26th 1853.

.....

The schedule referred to in these Letters Patent and making part of the same.

.....

To all to whom it may concern:

Be it known that I, Jeremiah Hills, of Newtown, and County of Fairfield, in the State of Connecticut, have invented or produced a new design for Ladies Bombs, and I do hereby declare that the following is a full and exact description of the same reference being had to the annexed drawings making a part of this specification.

The design consists of loops, a, placed on the upper part of the bomb. - Each alternate loop is put through the others so as to form two chains in opposite direction across the back running parallel to each other and fastening at the
